UNITED STATES PATENT OFFICE.

CONYERS BUTTON, OF PHILADELPHIA, PENNSYLVANIA.

DESIGN FOR STOCKING-FABRIC.

Specification forming part of Design No. 5,100, dated July 11, 1871.

To all whom it may concern:

Be it known that I, CONYERS BUTTON, of Philadelphia, county of Philadelphia, State of Pennsylvania, have invented or produced a Design for Stocking-Fabric, of which the following is a specification:

The figure in the accompanying drawings represents my design for a stocking-fabric, the principal features of which are the stripes A, each composed of the groups of bars, as shown.

The space between the stripes A is occupied by a series of stripes, a a a.

Irrespective of the colors employed, I claim—
The design for a stocking-fabric, substantially as described, and as represented in and by the accompanying drawings.

In testimony whereof I have signed my name to this specification in the presence of two subscribing witnesses.

CONYERS BUTTON.

Witnesses:

Wm. A. STEEL,
HARRY SMITH.
